(57) **CLAIM**

The ornamental design for a light for vehicles, as shown.

DESCRIPTION

FIG. 1 is a front perspective view of a light for vehicles showing our new design;

FIG. 2 is a rear perspective view thereof;

FIG. 3 is a front elevation view thereof;

FIG. 4 is a right side view thereof;

FIG. 5 is a left side view thereof;

FIG. 6 is a bottom plan view thereof;

FIG. 7 is a top plan view thereof; and,

FIG. 8 is a rear elevation view thereof.

The broken lines show portions of the light for vehicles that form no part of the claimed design.
